UNITED STATES PATENT OFFICE.

JOEL DE WITT JUSTIN, OF BADIN, NORTH CAROLINA.

AUTOMATIC GATE OPERATING MEANS FOR DAMS.

1,344,043.

Specification of Letters Patent. Patented June 22, 1920.

Application filed July 20, 1918. Serial No. 245,841.

To all whom it may concern:

Be it known that I, JOEL D. JUSTIN, a citizen of the United States, residing at Badin, in the county of Stanly and State of North Carolina, have invented certain new and useful Improvements in Automatic Gate-Operating Means for Dams, of which the following is a specification, reference being had to the accompanying drawings.

10 This invention relates to dams, and more particularly to devices for regulating the head of water behind a dam.

In the construction of dams or reservoirs, particularly in water power installations, it is, in almost all cases, essential to maintain a constant elevation of headwater, one reason for this being that an increase in the level of the headwater above the normal would flood valuable property and otherwise do a good deal of damage. Many types of gates have been designed for this purpose, but so far as I know, none of these gates are automatic in their action but depend, to a great degree, on the watchfulness 25 of operators. Some few gates have been designed to be partially automatic, but as far as I know none are fully automatic. If the operators are away or negligent, or if the machinery for operating the gates refuses to work, then when a flood comes disaster is the result, or if not absolutely disastrous, there is at any rate damage to the upstream banks.

The object of this invention is to provide 35 a gate which is operated automatically to control the level of the headwater so that when this level rises above a predetermined point, the gate shall be opened to a greater or less extent to permit the escape of the water and the reduction in its head.

A further object is to provide a construction of this character in which, upon a decrease of the headwater from an abnormal level, the gate will return automatically to 45 its normal position.

A further object is to provide a construction of this character in which the pressure of the headwater itself is utilized to keep the gate in position and automatically regulate the elevation at which the crest of the gate stands.

A further object is to provide in constructions of this character, a regulating device which is shifted by any increase in pressure 55 due to a rise in level of the headwater and which, when shifted under this increase in

pressure, causes the gate to be shifted so as to allow a greater amount of water to pass over the dam and thus reduce the level of the water behind the dam, this regulating device being such that it will return to its initial position upon a reduction of this pressure to normal and thereby cause the gate to return to its original position.

A further object is to provide a construction of this character in which the reaction of the regulating device to the pressure of the headwater may be adjustably controlled.

Other objects will appear in the course of the following description.

My invention is illustrated in the accompanying drawings, wherein:—

Figure 1 is a top plan view of a dam having gate operating means according to one form of my invention;

Fig. 2 is a section on the line 2—2 of Fig. 1;

Fig. 3 is a section on the line 3—3 of Fig. 2;

Fig. 4 is a section on the line 4—4 of Fig. 3;

Fig. 5 is a transverse vertical section of a dam having another form of gate and showing the controlling means therefor.

In Figs. 1 to 4, I have illustrated my regulating device as applied to a dam having therein a gate which shifts downward into a chamber formed in the dam to thereby allow the headwater to escape over the top of the gate. In these figures 10 designates a dam proper and 11 the usual abutments. Intermediate abutments or piers 12 may be disposed between the main abutments 11, all of these piers or abutments extending above the upper face of the dam. The abutments 11 and 12 are formed with vertical grooves 13 to receive the gate or gates 14 and the upper part of the dam is formed with a vertical pressure chamber 15, one for each gate into which the gate lowers. Normally the gate is raised to the position illustrated in Fig. 2, so that the crest of the gate is on a level with the normal level of the headwater.

The gate 14 may be of any suitable construction, but I have illustrated it as a hollow gate formed of inner and outer plates. Preferably holes 17 are provided in the downstream face of each plate for drainage and preferably the upstream plate of the gate extends above the downstream plate as at 18. Any suitable means may be provided

for preventing the passage of water around the lower end of the gate so as to retain the pressure within the chamber 15 and I have illustrated for this purpose the water-proofing strips 19 attached to the gate. For the purpose of preventing silt from getting into the pressure chamber 15, I may provide the rollers 20 mounted upon the dam on each side of the gate and bearing against the gate. The gate is limited in its downward movement by stops 21 projecting into the pressure chamber and in its upward movement by stops 22 on the abutments. Roller bearings are preferably provided in the channel 18 against which the gate bears.

For the purpose of controlling the vertical movement of the gate, I form in one of the abutments 11 of the dam, a chamber 23 and dispose in this chamber the outside cylinder 24. This cylinder carries at its upper end a collar 25 which is interiorly screw-threaded to engage screw-threads upon the exterior of the cylinder 24 and forms an extension of the cylinder 24. The upper end of this collar is formed with an inwardly extending stop flange 26. The cylinder 24 is connected adjacent its lower end to a pipe 27 which communicates with the pressure chamber 15. If there are a plurality of these chambers 15 corresponding to a plurality of gates, then there is communication between one chamber and the next adjacent chamber, so that the cylinder 24 communicates with all of the chambers. The cylinder 24 has an outlet pipe 28 connected thereto above the laterally extending pipe 27, this outlet pipe leading to the tail water through a duct formed in the corresponding abutment 11. Above the pipe 28 the cylinder 24 connects with an inlet pipe or duct 29 leading from the upstream face of the dam, this being disposed below the concrete crest of the dam, that is, below the top of the body of the dam and considerably below the normal level of the upper end of the gate.

Operating within the cylinder 24 is an inside cylinder 30 constituting a valve, this cylinder being closed at its upper end and open at its lower end and being formed with a lateral port 31 which in the normal position of the cylinder communicates with the inlet duct or pipe 29. The cylinder is provided with a stop flange 32 which normally bears against the upper edge of the cylinder 24 which constitutes a stop therefor and which coacts with the flange 26 when the cylinder is raised to its full height. Mounted upon the upper end of the valve 30 are a plurality of counterweights 33, these weights being so mounted upon the upper end of the valve that they may be readily removed therefrom or applied thereto in order to adjust the downward pressure on the valve.

In the normal position of the parts, as

above described, the valve 30 is lowered to the position shown in Fig. 3, and in this position the inlet pipe 29 has communication through the port 31 with the pipe 27 leading to the pressure chamber 15, while outlet 70 through the tail water pipe 28 is cut off. The pressure of water behind the dam will therefore exert a lifting force upon the gate, holding it in its raised position, but if this lifting force increases beyond a predetermined normal amount, due to a rise in the water and an increase in head then the pressure within the valve will increase and the valve will move upward against the action of the weights 33. When this occurs the 80 port 31 will move out of registry with the inlet pipe 29, thus cutting off the supply of water to the pressure chamber and opening communication between the pressure chamber and the outlet pipe 28. Hence the weight 85 of the gate will cause it to move downward forcing the water within the chamber 15 out through the outlet pipe 28 and, of course, lowering the effective level of the dam, permitting a greater volume of water to pass 90 over the dam, and thus lowering the height of the upstream water. When, however, the water level falls to normal, the pressure within the valve will decrease and the weights 33 will urge the valve downward to 95 its normal position cutting off the outlet of water from the pressure chambers and permitting the pressure of the upstream water to again raise the gate.

In Fig. 5, I show another form of gate 100 operated, however, on exactly the same principle as heretofore described and using the same controlling means. Referring to this figure, the dam 34 is, in this case, provided with a lifting gate 35 instead of a sinking gate. In other words, with this gate when it is desired to reduce the level of water against the upstream face of the dam, the gate is raised allowing the water to pass out between the lower edge of the gate and the upper face of the dam, whereas in the previous example the gate was lowered for this purpose. The gate 35 moves in grooves or channels in the jambs of the gate opening and is provided with any suitable packing 115 and with anti-friction bearings. It is not thought necessary to illustrate or describe these arrangements as they are those commonly found in gates of this character. The gate is counterweighted by means of 120 counterweights 36 disposed in vertical chambers 37 formed in the dam, cables 38 passing to the counterweights over pulleys 39. Preferably the counterweight chambers 37 are connected by means of a conduit or pipe 40. 125 The dam is also formed at one abutment with the chamber 41 within which the regulating device is disposed, this device being of the same character as illustrated in Figs. 3 and 4, in connection with the other gate. 130

Therefore, the same reference numerals have been used for this construction. In this case, the cylinder 24 connects by the passage 27 to the pressure chambers 37 wherein the 5 counterweights move, each counterweight being shiftable upon guides 42. It will therefore be seen that in this mechanism it is the counterweights against which the pressure of the headwater acts. Now in 10 this case when the level of the water behind the dam is normal, the valve 30 is at its lowest position causing the water behind the dam to pass through the inlet 29, through the port 31 and out through the pipe 27 to 15 the pressure chamber 37. If, however, the level of water rises beyond the normal, the pressure of the water will act to lift the valve as previously stated, and this will cut off the inlet of water and the water which 20 is in the pressure chamber or chambers will flow out through the duct or pipe 28 so that the counterweights 36 will no longer be partially supported by the water and, as a consequence, these counterweights will lower 25 raising the gate and allowing the superabundant water to flow off. When the head has been reduced to a proper level, the valve will again shift to its normal position and pressure will be directed into the pressure 30 chambers 37 and this will cause the counterweights to lift so that the gate will overbalance the counterweights and return to its normal position.

I have described two applications of my 35 invention for illustrative purposes, but it will be understood that the automatic pressure controlled valve mechanism described may be used for the purpose of controlling any gate whether the gate is a sector gate, 40 or, for instance, a gate which rises to permit the escape of water, or a gate which lowers to permit the escape of water, and I wish it understood that I do not consider that my invention is limited to any particular 45 form of gate as any gate which may be shifted by the direct pressure of water or by the pressure of water on counterweights is adapted to be controlled by my automatically acting pressure controlled mechanism.

50 It may be noted that in Figs. 1 to 4, I show a gate having a sharp crest 18. Thus the nappe of the discharging water over the gate or caisson will break clear and free and jump the remainder of the caisson or gate. 55 In order to accomplish this the nappe must be aerated by pipes 43. It is to be particularly noted that by increasing or decreasing the number of weights on the valve, the normal headwater elevation may be controlled 60 at any time. Further, it will be noted that with my mechanism, a large difference of level between the headwater and tail water is not an important factor. It will be seen that I have provided in combination with a spillway gate supported in

part or whole by the headwater pressure, a device actuated by the headwater pressure which automatically operates the gate on an increase or decrease in the elevation of the headwater. 70

In a dam including a number of gates, it may be desirable to have several regulating devices, with all of the pressure chambers connected together but, on the other hand, the regulating devices may be arranged so 75 that they are entirely independent one of another. It is also desirable in many cases to use gate valves or other valves on the inlet and outlet pipes of the regulating device, that is, on the pipes 27, 28, and 29, in 80 order to secure, by adjusting these valves, the exact degree of sensitiveness desired in the regulating device.

Instead of having all of the gates act at one time, it may be desirable to have them 85 act in succession, one after the other as the headwater increases. This may readily be accomplished by varying any or all of the following factors: The weights 33 on top of the regulating device; the counterweights 90 36, and the weighted gate itself. Such variations would have to be determined for each particular site, according to existing conditions.

Having described my invention, what I 95 claim is:—

1. In a dam, a spillway gate urged to a discharge position by gravity, a water pressure chamber so connected to the gate that the pressure of water therein urges the gate 100 to its normal position, and a valve operated automatically by an abnormal increase of pressure of head water to relieve the pressure of water within the water chamber to thereby permit the gate to shift to a discharge position.

2. In a dam, a spillway gate shiftable toward or from a normal position, a water pressure chamber coacting with the gate, the water pressure therein acting to urge 110 the gate to its normal position, a valve chamber having an inlet duct receiving headwater, an outlet duct discharging water from the chamber, a duct leading to the water pressure chamber, and a valve normally establishing communication between the water pressure chamber and the inlet duct, but cutting off outlet from said valve chamber, said valve being shiftable upon an increase of pressure in the headwater 120 to a position cutting off the supply of water to the pressure chamber and establishing communication between the pressure chamber and the outlet duct whereby to reduce the pressure in the pressure chamber and 125 permit the gate to shift to a discharge position.

3. A dam including a spillway gate shiftable toward or from a normal position and urged by gravity to a discharge position, the 130

gate being held in its normal position by the pressure of head water, a controlling member for the gate yieldably held in a position to maintain the water pressure acting upon the gate but, upon an increase of head water pressure beyond a predetermined point shifting to a position to relieve the pressure of water acting upon the gate to thereby permit the gate to shift to a discharge position, and means for adjustably controlling the resistance said member offers to head water pressure whereby said member may be adjusted to operate under different pressures of head water.

4. A dam including a spillway gate shiftable toward or from a normal position and urged from its normal to its discharge position by gravity, a pressure chamber operatively connected to the gate and to a source of head water, the pressure of head water in the pressure chamber yieldingly holding the gate in its normal position, means shiftable by and with predetermined variations in head water pressure controlling the admission of water to said pressure chamber or the discharge of water therefrom, and means adjustably resisting said movement of said pressure controlled means, whereby the pressure controlled means may be adjusted to act under different head water pressures.

5. A dam including a spillway gate shiftable toward or from a normal position and urged by gravity to a discharge position, a water pressure chamber operatively connected to the gate to support the gate in its normal position by water pressure, a valve chamber having an inlet connected to the upstream face of the dam, an outlet for tail water communicating with said pressure chamber, and a valve therein yieldingly urged to its normal position, said valve in its normal position establishing communication between the inlet of the valve chamber and the pressure chamber, cutting off communication between the valve chamber and the tail water outlet, said valve shifting under an increase of headwater pressure to cut off communication between the inlet and the valve chamber and establish communication between the outlet and the water pressure chamber.

6. A dam including a spillway gate shiftable toward or from a normal position and urged by gravity to a discharge position, a water pressure chamber operatively connected to the gate to support the gate in its normal position by water pressure, a valve chamber having an inlet connected to the upstream face of the dam, an outlet to tail water communicating with said pressure chamber, and a vertically shiftable valve in the valve chamber urged to a normal position by gravity and in this normal position establishing communication be-

tween the headwater and the pressure chamber but cutting off outlet from the valve chamber, said valve being shiftable by an increase in pressure in the headwater to a position where it will establish communication between the pressure chamber and the outlet and cut off communication between the valve chamber and the inlet.

7. A dam including a spillway gate shiftable toward or from a normal position and urged by gravity, to a discharge position, a water pressure chamber operatively connected to the gate to support the gate in its normal position by water pressure, a valve chamber having an inlet connected to the upstream face of the dam, an outlet to tail water communicating with said pressure chamber, and a vertically shiftable valve in the valve chamber urged to a normal position by gravity and in this normal position establishing communication between the headwater and the pressure chamber but cutting off outlet from the valve chamber, said valve being shiftable by an increase in pressure in the headwater to a position where it will establish communication between the pressure chamber and the outlet and cut off communication between the valve chamber and the inlet, the valve and valve chamber having coacting stops limiting the movement of the valve.

8. A dam including a spillway gate shiftable toward or from a normal position and urged by gravity to a discharge position, a water pressure chamber operatively connected to the gate to support the gate in its normal position by water pressure, a valve chamber having an inlet connected to the upstream face of the dam, an outlet for tail water communicating with said pressure chamber, and a vertically shiftable valve in the valve chamber urged to a normal position by gravity and in this normal position establishing communication between the headwater and the pressure chamber but cutting off outlet from the valve chamber, said valve being shiftable by an increase in pressure in the headwater to a position where it will establish communication between the pressure chamber and the outlet and cut off communication between the valve chamber and the inlet, the valve being urged to its normal position by a plurality of detachable weights.

9. A dam including an abutment, a spillway gate shiftable toward or from a normal position and yieldingly held in its normal position by the action of gravity, a water pressure chamber, a member movable within the water pressure chamber and forming part of the gate and urged to a normal position by the pressure of water within the chamber, a cylindrical valve chamber mounted in the abutment and having an inlet leading from the upstream face of the

dam, and an offset outlet discharging on the downstream side of the dam, there being communication between the valve chamber and the water pressure chamber, and a cylindrical valve disposed within the cylindrical valve chamber and vertically shiftable therein and having a port normally communicating with the inlet, said valve in its normal position extending across the outlet 5 and thereby establishing communication between the inlet and the pressure chamber, said valve when lifted by an increase in pressure of the headwater above normal carrying its port past the inlet opening of 10 the valve chamber and establishing communication between the water pressure chamber and the outlet.

15 10. A dam including abutments, the body of the dam being formed with a longitudinally extending gate receiving recess, a gate shiftable downward into said recess, the recess forming a water pressure chamber, the pressure of water within this chamber controlling the position of the gate, a valve

chamber having an inlet connected to the upstream face of the dam, an outlet for tail water and said valve chamber communicating with said pressure chamber and with the downstream face of the dam, and a vertically shiftable valve in the valve chamber 20 urged to a normal position by gravity and in this normal position establishing communication between the headwater and the pressure chamber but cutting off outlet from the valve chamber, said valve being shiftable by an increase in pressure in the headwater to a position where it will establish communication between the pressure chamber and the outlet and cut off communication between the valve chamber and the inlet, the valve being urged to its normal position by weights.
